UNITED STATES PATENT OFFICE.

FRANK MACEY, OF GRAND RAPIDS, MICHIGAN.

MEANS FOR OPERATING DOORS.

SPECIFICATION forming part of Letters Patent No. 703,433, dated July 1, 1902.

Application filed December 24, 1900. Serial No. 40,898. (No model.)

To all whom it may concern:

Be it known that I, FRANK MACEY, a citizen of the United States, residing at Grand Rapids, in the county of Kent and State of Michigan, have invented certain new and useful Improvements in Means for Operating Doors; and I do hereby declare the following to be a full, clear, and exact description of the invention, such as will enable others skilled in the art to which it appertains to make and use the same.

My invention relates to improvements in means for operating doors, and more particularly to operating the doors of book-cases and other like articles of furniture having doors adapted to turn from a vertical to a horizontal position and to run back into the case.

The object of my invention is to provide a cheap and simple device adapted to cause the door to run back into the case automatically, to guide the door so that it will run freely without binding, to hold the door closed at the bottom, and to provide the device with certain new and useful features hereinafter more fully described, and particularly pointed out in the claims.

My device consists, essentially, in combining with the door a spring-actuated roll and cords wound on said roll by the action of the spring and attached to the door and opposing cords also connected to the door and roll, together with certain guide-rolls engaging the cords, as will more fully appear by reference to the accompanying drawings, in which—

Figure 1 is a plan view of a device embodying my invention; Fig. 2, an enlarged partial vertical section showing an inside end elevation of the same; Fig. 3, a detail in vertical section on the line 3-3 of Fig. 1; Fig. 4, a detail showing an inside elevation of an upper corner of the door and parts adjacent; Fig. 5, a detail showing one end of the spring-actuated roll and parts adjacent, and Fig. 6 a perspective detail of a hook-plate.

Like letters refer to like parts in all the figures.

A represents a portion of a book-case.

B is the door of the case, adapted to turn to a horizontal position and slide inward on ways C in the ends of the case.

D is a spring-actuated roll journaled in the

ends of the case and extending across the upper rear portion thereof.

F is a suitable spring for actuating the roll D, having one end secured to the roll D and the other end held stationary by connecting the same to the rear wall of the case. This spring tends to rotate the roll in the direction indicated by the arrow in Fig. 2 and winds the cords G on the roll D. These cords are attached to the roll D and extend to the front B and are attached thereto, whereby when the front is raised to a horizontal position the cords G pull the front back into the case. Extending from the opposite side of the roll D and winding oppositely thereon are cords G', which are also attached to the front and engage grooved guide-rolls I, journaled on suitable supports near the front of the case.

The cords G' are also engaged with other guide-rolls H beneath the roll D, whereby the cords are held below the plane of the front and the roll D also held in place. The cords G' are thus wound upon the roll D as the cords G are unwound and are unwound therefrom as the cords G are wound thereon. The cords G and G' being oppositely wound upon the roll D and extending in a circuit around the roll I and attached to the front are strained tight at all times and operate to so limit the movement of the front at its respective ends that it moves simultaneously exactly the same distance at each end, thus effectually preventing all binding of the door in the case.

To adjustably attach the cords to the front and to provide pivot-hooks for the front, plates K are attached to the front by suitable screws and provided with inwardly-projecting hooks J at one side, adapted to engage the supports for the rolls I and pivotally support the door thereon. Said plates are also provided with openings K' and K'', through which the cords G and G' are inserted and extended between the plate and the front, being thus securely attached to the front and readily adjusted by loosening the screws that hold the plate.

The cord G is attached below the supports for the roll I, and the cord G' extends beneath the said roll and thence upward, whereby the strain on said cords tends to hold the front closed at the bottom. When the front is opened, the cord G passes the support for the roll I. Thus when the door is closed and the cord below

the supports for the roll I the tension of the spring holds the front closed, and when the front is horizontal the cord G is above the axis of the said supports and the spring tends to 5 pull the front into the case.

To provide a reduced middle portion to the roll D to economize space and material and provide room for the spring F and also securely attach the pivot-pins M thereto, the 10 roll is made in three parts, the middle consisting of a suitable round rod E, the ends E' consisting of cylindrical portions of larger diameter and having an axial opening extending throughout and reduced at one end to receive a suitable headed rivet M, forming a pivot-pin. The end of the rod D abuts against the head of the pin M and securely holds it in place in the roll. The spring F is secured to the roll by inserting one end of the same 15 in the portion E', and the other end is held stationary by inserting it in an opening in the spring-case L, as at F'. This spring-case consists of a suitable piece of sheet metal bent in semicylindrical form extended in parallel 20 planes and flanged and secured to the back of the case. The roll is detachably journaled in the case A by inserting the pivot-pins M in upwardly-open slots M' in the ends of the said case and is held therein by the engagement 25 of the cords G' with the rolls H.

Having thus fully described my invention, what I claim, and desire to secure by Letters Patent, is—

1. In combination with a case and a front 35 adapted to run into the case, a roll, a spring to rotate the roll, cords attached to the front and wound upon the roll by the action of the spring and operating to pull the front into the case, and cords attached to the front and 40 oppositely wound upon the rolls and acting to restrain the inward movement of the front, substantially as described.

2. The combination of a case, a front adapted to turn from vertical to horizontal position 45 and run back into the case, a roll journaled in the case, a spring to rotate the roll, cords attached to the roll and front and wound on the roll by the spring, and cords wound on the roll oppositely to the first-named cords, 50 and attached to the front, and guide-rolls at the front of the case engaging the last-named cords, substantially as described.

3. The combination of a case, a front adapted to turn to a horizontal position and run 55 into the case, a roll journaled in the case, a spring to operate the roll, cords attached to the roll and front and wound on the roll by the action of the spring, cords wound on the roll oppositely to the first-named cords and 60 attached to the front, and guide-rolls near the front and rear of the case, and engaging the last-named cords, substantially as described.

4. The combination of a case, a front adapted to turn from vertical to horizontal and to 65 run back into the case, hooks on the front, a support at the front of the case pivotally and

detachably engaged by the hooks, a spring to constantly pull inward on the front, means for connecting the spring to the front at a 70 point shifting from below the supports when the front is vertical, to above the supports when the front is horizontal, whereby the bottom of the front is held closed when the front is vertical, and the front pulled into the case 75 when the front is horizontal, substantially as described.

5. The combination of a case, a front, adapted to turn from vertical to horizontal position, a hook, on the front, a support at the front 80 of the case pivotally engaged by the hook, a roll journaled in the case, a spring to rotate the roll, and a cord attached to the roll, and wound on the same, and also attached to the front, below the support, whereby the spring 85 pulls the lower part of the front inward, holds the front closed when the front is vertical and pulls the front into the case when the front is horizontal, substantially as described.

6. The combination of a case, a front, a 90 roll journaled in the case, cords connecting the roll and front, supports near the front of the case, plates attached to the front having openings to receive the cords, and hooks on the plates engaging the supports, substantially as described.

7. The combination of a case, a front, a roll journaled in the case, a spring to operate the roll, cords wound on the roll by the spring and connected to the front, guide-rolls near the 100 front of the case, cords attached to the spring-actuated roll and engaging the guide-rolls, plates having openings to receive the cords and attached to the front, hooks on said plates to engage the supports of the guide-rolls, and 105 screws to adjustably secure the plates and clamp the cords between the plates and the front, substantially as described.

8. The combination of a case having upwardly-open slots, a roll detachably journaled 110 in the slots, guide-rolls below said roll, a front, cords connecting the roll and front and engaging said guide-rolls, guide-rolls near the front of the case engaged by said cords, and cords extending directly from the roll to the 115 front, substantially as described.

9. The combination of a case, a front adapted to turn from vertical to horizontal position, hooks on the front, supports at the front of the case pivotally engaged by the 120 hooks, guide-rolls on the supports, a roll journaled in the case, a spring to rotate the roll, cords wound on the roll by the spring and connected to the front below the supports, when the front is closed, and adapted to pass 125 above the rolls and supports when the front is opened, and cords wound on the rolls oppositely to the first-named cords, and passing under the guide-rolls and thence upward and attached to the front above the guide-rolls, 130 substantially as described.

10. The combination of a case, a front adapted to turn from vertical to horizontal position and run back into the case, a roll

journaled in the case, cords wound on the roll and attached to the front, and cords wound on the roll oppositely to the first-named cords and also attached to the front, 5 and guide-rolls at the front of the case engaging the last-named cords, whereby the front is prevented from binding in the case, substantially as described.

11. The combination of a case, a front 10 adapted to turn from vertical to horizontal position and to run back into the case, a roll,

cords oppositely wound on the roll, and operating to limit the movement of the front and prevent binding of the same in the case, a spring to rotate the roll, substantially as 15 described.

In testimony whereof I affix my signature in presence of two witnesses.

FRANK MACEY.
